UNITED STATES PATENT OFFICE.

EDWARD THIMOTHY FORD AND FRANK FORD WASSAM, OF DUNKIRK, INDIANA.

RAIL-FASTENING DEVICE.

No. 906,402.

Specification of Letters Patent.

Patented Dec. 8, 1908.

Application filed February 12, 1908. Serial No. 415,591.

To all whom it may concern:

Be it known that we, EDWARD T. FORD and FRANK F. WASSAM, citizens of the United States, residing at Dunkirk, in the county of Jay and State of Indiana, have invented certain new and useful Improvements in Rail-Fastening Devices; and we do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to new and useful improvements in fastenings for railway rails, and comprises various details of construction, combinations and arrangements of parts which will be hereinafter fully described and then specifically defined in the appended claims.

We illustrate our invention in the accompanying drawings, in which:

Figure 1 is a perspective view showing the fastening as applied to rails and ties. Fig. 2 is a cross sectional view. Figs. 3 and 4 are detail views, and Fig. 5 is a detail view of a modification showing the plates for clamping the flanges of the rails, extending only preferably the width of the ties.

Reference now being had to the details of the drawings by letter, A designates ties, preferably of metal, and are reinforced by suitable ribs and have chambered portions B through the walls of which are formed the transverse slots C—C which register.

E designates rails of a railway which rest upon the upper flat top of the ties over said chambered portion.

F—F designate fish plates or splice bars, each extending over two ties, and each of which bars having one or more projections extending beneath the bottom of the rail, and each projection being provided with an integral finger H having a threaded end D' adapted to receive a nut J. Said finger is designed to pass through one of the slots C and the laterally projecting portion I' of the fish plate is adapted to rest upon shoulders A' formed in the upper surface of the ties. Each fish plate has the integral fingers posi-

tioned in different directions upon opposite sides of the rails and, after the fish plates have been adjusted in place, bolts N are passed through registering apertures therein and the webs of the rails to be fastened together.

From the foregoing, it will be noted that, by the provision of a fastening device as shown and described, a simple and efficient means is afforded for securely holding the rails rigidly upon the ties and affording mechanism whereby the parts are held from becoming loosened.

What we claim to be new is:—

1. A rail fastening device comprising, in combination with a tie having horizontal apertures formed therein, plates adapted to engage the flange of the rail and having integral fingers adapted to be passed through the horizontal apertures in the ties, and means for fastening said fingers, as set forth.

2. A rail fastening device comprising, in combination with a tie having horizontal apertures formed therein, plates adapted to engage the flange of the rail and having integral fingers adapted to be passed through the horizontal apertures in the ties, the ends of said fingers being threaded, and nuts mounted upon the threaded ends of the fingers, as set forth.

3. A rail fastening device comprising, in combination with a rail having transverse apertures formed therein, a rail clamping plate having a finger extending parallel with the plate and designed to be inserted through one of said apertures, and a nut mounted upon the threaded end of the finger, as set forth.

4. A rail fastening device comprising, in combination with ties having chambered portions, the walls of said chambered portions having registering apertures therein, a rail clamping plate having an integral finger extending parallel with the plate and threaded at its end, said finger designed to be passed through registering apertures in the tie, and a nut mounted upon the threaded end of the finger, as set forth.

5. A rail fastening device comprising, in combination with ties having transverse apertures therein, a plate designed to clamp over the flange and the bottom of the rail and

having an integral finger with a threaded end, said finger designed to be passed through the transverse aperture of the tie, a nut fitted to the threaded end of the finger, said plate having a shoulder upon its outer face adapted to rest upon a transverse shoulder upon the upper surface of the tie, as set forth.

In testimony whereof we hereunto affix

our signatures in the presence of two witnesses.

EDWARD THIMOTHY FORD.
FRANK FORD WASSAM.
